CLAIM

The ornamental design for a combined turning and milling machine, as shown and described.

DESCRIPTION

FIG. 1 is a front perspective view of a combined turning and milling machine showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines are shown for illustration purposes only and form no part of the claimed design. The present article is a multi-tasking machine having the functions of turning and milling operations.
